W. M. SANDEFUR,
TOOL FOR GRINDING WATCH CRYSTALS.
APPLICATION FILED SEPT. 2, 1920.

1,418,975.

Patented June 6, 1922.

Inventor

W. M. SANDEFUR,

Franklin H. Abugh
Attorney

UNITED STATES PATENT OFFICE.

WILLIAM MALLOW SANDEFUR, OF DURANT, OKLAHOMA.

TOOL FOR GRINDING WATCH CRYSTALS.

1,418,975.

Specification of Letters Patent. Patented June 6, 1922.

Application filed September 2, 1920. Serial No. 407,631.

To all whom it may concern:

Be it known that I, WILLIAM MALLOW SANDEFUR, a citizen of the United States, residing at Durant, in the county of Bryan

5 and State of Oklahoma, have invented certain new and useful Improvements in Tools for Grinding Watch Crystals; and I do hereby declare the following to be a full, clear, and exact description of the invention, 10 such as will enable others skilled in the art to which it appertains to make and use the same, reference being had to the accompanying drawings, and to the letters and figures of reference marked thereon, which form a 15 part of this specification.

This invention, while relating generally to grinding and polishing machines and tools, has more particular reference to a simple tool for grinding watch crystals.

20 Almost all tools for this purpose on the market are rather expensive and slow in operation, since practically all are lathe attachments. In fitting crystals it is necessary to try the same in the watch bezels at short 25 intervals when grinding them down, since there is very little difference between a crystal that fits and one that is a trifle too small. Therefore, in order to do this with lathe machines, the operator has to take 30 the glass out of the lathe machine and try the same in the watch bezel, and put it back in the lathe again, which requires time to recenter.

The object of my invention is to provide a 35 very simple file for watch crystals which obviates the use of a lathe, and which has the advantage of speed in use.

With this object in view, the invention resides in a tool for the purpose described, 40 characterized by the provision of a back-plate, removably carrying clamping members for a plurality of superposed sand- paper strips disposed upon said back-plate, and securely held by said clamping members 45 in use.

The accompanying drawing clearly discloses the preferred form of my invention, although it is to be understood that I do not desire to be restricted thereto, since changes 50 may be made within the scope of the appended claim without departing from the spirit of the invention, or necessarily sacrificing any of its advantages. Briefly described:

55 Figure 1 is a view in perspective of the tool of my invention;

Figure 2 is a fragmentary view in side elevation thereof;

Figure 3 is a fragmentary view in bottom plan, and

Figure 4 is a detached detail view in perspective of one of the clamping members.

Referring now in detail to the drawing:

1 designates a base, or back-plate, which may be of any preferred length for convenient manipulation by the operator. Said plate is provided with two apertures 2, 2, through each of which projects a stem 3, carried by a clamping member 4, the latter being preferably constructed as a plate having angled terminals 5, 5, one of said terminals being adapted, in use, to bear against the base plate 1, and the other of the terminals against a plurality of superposed sand-paper sheets, or strips, 6. The terminal of each stem 3 is exteriorly threaded, as shown at 7, for the reception of a wing-nut 8, which is screwed upon said threaded extremity to clamp the plate 1 against the sand-paper 6, a washer 9 being interposed 75 between the nut 8 and the base plate 1.

In operation, the parts are assembled as shown in Figures 1, 2 and 3 with the clamping members 4, 4 tightly holding the sand-paper 6 against the base plate 1, and the tool 80 is used by reciprocating the same against the watch crystal. The sand-paper 6, used in connection with my tool, is very fine, so that the glass of the watch crystal will not be chipped, as is the result when the common 85 steel file, used by many operators, is utilized. My tool, using fine sand-paper, also leaves the edge of the crystal so smooth that it is not noticeable when it has been ground down. I have found by experiment that it 90 is advisable to use about ten strips of sand-paper in connection with the tool, and when one strip of paper begins to stop cutting, the same is torn off and the user of the tool has another good surface.

I have also found, in operation, that by the use of a plurality of superposed sand-paper strips, I obtain a cushioning effect which makes the tool cut much faster and more evenly.

Having thus described my invention, the many advantages thereof will be apparent, especially to those skilled in the art to which it pertains.

What I claim to be new and upon which I 110 desire to obtain Letters Patent is:

A hand buffer comprising a back plate for

receiving a plurality of superposed abrasive strips, said back plate provided with a pair of openings, a pair of clamping means each consisting of a plate having a comparatively long, right-angled bent portion at one end thereof, providing a fulcrum for said plate, a relatively short right-angled bent portion at the opposite end thereof for securely holding the abrasive strips to the back plate,
10 a threaded extension integral with the plate

and projecting through the opening in the back plate, said opening being sufficiently large to permit the positive gripping of a maximum or minimum number of abrasive strips by its coacting bent portion, and a 15 wing nut in threaded engagement with the threaded extension.

In testimony whereof I hereunto affix my signature.

WILLIAM MALLOW SANDEFUR.
